DESIGN FOR A BOWLING ALLEY

Karl Gromann, Bloomfield, N. J.

Application March 3, 1937, Serial No. 67,952

Term of patent 7 years

To all whom it may concern:

Be it known that I, Karl Gromann, a citizen of the United States, residing at Bloomfield, in the county of Essex, State of New Jersey, have invented a new, original, and ornamental Design for a Bowling Alley, of which the following is a specification, reference being had to the accompanying drawing, forming a part thereof.

Figure 1 is a plan view of a bowling alley, showing my new design.

Figure 2 is a side elevation of Figure 1.

Figure 3 is an end view at the point 3 of Figure 2.

Figure 4 is a view across the alley on the line 4—4 of Figure 2.

Figure 5 is a view across the alley on the line 5—5 of Figure 1.

The characterizing features of my design reside in the bowling alley of the proportions and

configuration shown, having a series of pairs of leg members provided with inclined bracing members at the upper portions thereof imparting a bridge-like appearance thereto, with ball-retarding members substantially triangular in cross section positioned in the runways near the front ends thereof, and a guard member surrounding the alley pit, in height equal to substantially four times the height of the guard surrounding the main portion of the alley and merging therewith by a sloping ogee curve and being partly enclosed at the top by a horizontal covering of substantially half the width of the pit of the alley and extending slightly beyond the sides of the guard.

I claim:

The ornamental design for a bowling alley, as shown and described.

KARL GROMANN.
